UNITED STATES PATENT OFFICE.

JOHN W. HENRY, OF CRAWFORDSVILLE, INDIANA.

METHOD OF MAKING RUGS.

1,361,055.

Specification of Letters Patent.

Patented Dec. 7, 1920.

Application filed July 18, 1919. Serial No. 311,725.

To all whom it may concern:

Be it known that I, JOHN W. HENRY, a citizen of the United States, residing at Crawfordsville, in the county of Montgomery and State of Indiana, have invented a new and useful Method of Making Rugs, of which the following is a specification.

The objects of this invention are, first, to provide a rug frame of novel form, whereby 10 a selvage may be made, in a known process, along one edge of a rug, which, heretofore, has been provided with a fringe.

Another object of the invention is to provide an improved step in the process of 15 making the rug, whereby a cutting of the base net will be avoided.

Another object of the invention is to improve the construction of the rug.

It is within the province of the disclosure 20 to improve generally and to enhance the utility of devices of that type to which the invention appertains.

With the foregoing and other objects in view, which will appear as the description 25 proceeds, the invention resides in the combination and arrangement of parts and in the details of construction hereinafter described and claimed, it being understood, that, within the scope of what is claimed, 30 changes in the precise embodiment of the invention shown can be made without departing from the spirit of the invention.

In the accompanying drawings:

Figure 1 shows in top plan, a portion of a 35 rug frame constructed in accordance with the invention, a rug being shown thereon, in the various steps of the manufacture of the rug; Fig. 2 is a sectional view showing how the fibers of the rug are prepared for cutting; Fig. 3 is a bottom plan diagrammatic in nature and showing sundry details; Fig. 4 is a side elevation showing the member whereby a compression of the fiber is effected, during the cutting operation; parts 40 appearing in section; Fig. 5 is a perspective illustrating the cutting operation; Fig. 6 is a plan showing the member delineated in Fig. 4 in duplicated form, the view disclosing a modification; Fig. 7 is a sectional detail illustrating a modification in the rug.

Numeral 1 denotes a frame, ordinarily of rectangular form and including end pieces 2, and side pieces 3. Pins 4 are mounted on the end pieces 2, and, as a distinctive improvement angle hooks 5 are mounted on the

side pieces 3, the hooks 5 having upstanding ends 6.

The frame above described is adapted to be used in a rug making process which is known and old, saving as to details herein-after pointed out. In carrying out this process, there is provided a base net 7, ordinarily made of cords, and including longitudinal strands 8 engaged with the pins 4, and transverse strands 9 engaged with pins on the side pieces 3 a known process, but in the present form of the invention, engaged with the ends 6 of the single hooks 9.

On the base net 7, constructed as above described, is placed a body 10, including 70 longitudinal fibers 11 and transverse fibers 12, the longitudinal fibers 11 being disposed above the longitudinal strands 8 of the base net and the transverse fibers 12 being disposed above the transverse strands 9 of 75 the base net. At the points where the transverse strands 8 and 9 cross, and where consequently, the fibers 11 and 12 cross the strands and the fibers are tied together as at 14, by means of a cord 15. The fibers 11 and 12 are cut as indicated at 16 in Fig. 1, between the points where the fibers cross the free ends thus produced upstanding to form tufts 17. The longitudinal fibers 8 of the base net 7 and the longitudinal fibers 10 are 80 cut as indicated at 30 to form a fringe 32. Heretofore this fringe has extended around all four sides of the rug, but, in the present improvement, and because the angle hooks 5 are used, the rug is provided along two of 90 its edges in a selvage strip 31, as distinguished from a fringe, the selvage strip being tied wherever necessary, as indicated at 33.

In making a rug according to the process 95 above described, considerable difficulty has been experienced when the fibers 11 and 12 are cut as shown at 16, because it is exceedingly difficult in practice to make this cut without severing not only transverse fibers 100 11 and 12 and the strands 8 and 9 as well, the result of course, being that the rug has a loose portion or a hole at the point where a complete severance of the fibers and the strands is made.

In order to avoid defects of the kind above mentioned, there is supplied a member or pin 18 provided in one end with a relatively shallow notch 19 and with a deeper notch 20. The transverse fibers 9 110

of the base net 7 and the corresponding fibers 12 of the body 10 or the strands 8 or the base net and the corresponding fibers 11 of the body, are engaged, between the 5 tied portions 14, in the deeper notch 20 of the pin 18. Then, the tuft is made by means of a knife 21 operated in the shallow notch 19. As a consequence from the foregoing, a tuft forming ends 22 result as shown in 10 Fig. 5, but as shown in that figure, the strands of the base net are severed. Further, certain of the fibers 10 and 11 are not severed, but remain intact as shown at 23, 15 above the strands of the base net, thereby covering the first transverse strands of the base net.

In the form of the invention shown in Fig. 6, the numeral 24 designates pins like the part 18, the notches 25 being of the sort 20 heretofore described, the pins being mounted on a body 26, the modification consisting essentially, in assembling the pins 18 in gangs. The body 26 may carry as many pins 24 as is considered expedient or necessary. 25

In Fig. 7, a modified form of rug is shown. The base net appears at 27 and the fibers are shown at 29. In this form of the invention, the body-forming fibers 30 are placed both above and below the base

net and, consequently, the rug is provided not only upon its upper surface, but upon its lower surface as well, with tufts 39 the rug, therefore, being reversible.

In describing the invention, the term 35 "rug" has been used, but it will be understood, that the resulting product is a fabric which may be used for purposes other than a rug.

Having thus described the invention, what 40 is claimed is:

In a process of the class described, which comprises placing crossed fibers on the crossed strands of a base net, securing the fibers and the strands at their points of 45 crossing, and cutting the fibers between their points of crossing to form tufts; that step which consists in compressing the fibers in the deeper of two intersecting notches of a member, and a cutting apart of the fibers 50 with a knife operated in the shallow notch of said member.

In testimony that I claim the foregoing as my own, I have hereto affixed my signature in the presence of two witnesses.

JOHN W. HENRY.
